INHIBITION OF CARBURETOR ICING

Harry J. Andress, Jr., Pitman, and Paul Y. C. Gee, Woodbury, N.J., assignors to Socony Mobil Oil Company, Inc., a corporation of New York

No Drawing. Filed Jan. 7, 1958, Ser. No. 707,460

3 Claims. (Cl. 44—71)

This invention relates to gasoline compositions adapted to improve the operation of internal combustion engines. It is more particularly concerned with motor fuels that provide improved engine operation under cool, humid weather conditions.

As is well known to those skilled in the art, frequent stalling of automobile engines, especially during the warmup period, has been a common occurrence. This difficulty is most pronounced in postwar cars having automatic transmissions and a consequent limit on the maximum permissible idle speed. Stalling of this type, of course, is a definite safety hazard, as well as a decided inconvenience in frequent restarting of the engine.

It is now recognized that stalling during the warmup period is attributable to the formation of ice on the throttle plate and the carburetor barrel near it. The water which forms the ice does not come from the gasoline, i.e., as entrained water, but from the air that enters the carburetor. As has been mentioned hereinbefore, stalling generally occurs in cool, humid weather, when the temperatures are above about 30° F. and below about 60° F. and the relative humidity is about 65 percent and higher, up to 100 percent. The most critical conditions are temperatures of 35–40° F. and 100 percent relative humidity.

As the gasoline evaporates in the carburetor, it reduces the temperature of the surrounding metal by as much as 50° F. Moisture in the incoming air comes in contact with these parts and begins to build up ice on the throttle plate and in the carburetor barrel. The more moist this air is, the greater the buildup of ice. Then, when the engine is idled, the throttle plate closes and the ice chokes off the normal small flow of air through the small clearance between the throttle plate and the carburetor wall. This causes the engine to stall. The engine can usually be restarted when the heat from the exhaust manifold melts the ice sufficiently. However, stalling will continue until the engine is completely warmed up.

Gasoline is a mixture of hydrocarbons having an initial boiling point falling between about 75° F. and about 135° F. and an end-boiling point falling between about 250° F. and about 450° F. The boiling range of the gasoline, of course, reflects on its volatility. Thus, a higher boiling gasoline will be less volatile and give less stalling difficulty. In modern engine operation, however, control of stalling by means of increased volatility is not feasible, because other performance characteristics are affected.

It has now been found that stalling during engine warmup can be overcome simply and economically. It has been discovered that small amounts of certain succinamic acids, when added to motor gasoline, will overcome stalling difficulties attributable to carburetor icing.

Accordingly, it is an object of this invention to provide an improved motor fuel. Another object is to provide a motor fuel adapted to prevent stalling during engine warmup in cool, humid weather. A specific object is to provide an antistall gasoline containing certain succinamic

2

acids. Other objects and advantages of this invention will become apparent to those skilled in the art, from the following detailed description.

In general, this invention provides a motor gasoline containing a small amount, sufficient to inhibit stalling, of compounds having the formula,

wherein R is an alkyl group containing between about 10 and about 30 carbon atoms and having a tertiary carbon atom directly attached to the nitrogen atom.

The addition agents utilizable in the improved gasolines of this invention are succinamic acids having the structural formula,

wherein R is an alkyl group containing between about 10 and about 30 carbon atoms per alkyl group and having a tertiary carbon atom directly attached to the nitrogen atom. The amic acids can be made by any method known in the art for preparing such compounds. Preferably, they are produced by warming succinic acid anhydride with a tertiaryalkyl primary monoamine having between about 12 and about 24 carbon atoms per molecule. This can be done readily by heating a mixture of equimolar amounts of the acid anhydride and the tertiaryalkyl primary amine at a temperature of 65–150 C. for a period of time varying between one and three hours. The addition occurs readily without the formation of water. Less desirably, the amic acids can be prepared by the controlled reaction between equimolar amounts of succinic acid and the amine, with the elimination of one mole of water per mole of amic acid produced. Care must be exercised, however, to avoid the elimination of two moles of water to form the cyclic imide.

The amines utilizable in forming the amic acids are the tertiaryalkyl primary monoamines in which a primary amino group (—NH₂) is directly attached to a tertiary carbon atom, and which contains between about 10 and about 30 carbon atoms per tertiaryalkyl group. The amines all contain the group,

Non-limiting examples of the amines are t-dodecyl primary amine, t-tetradecyl primary amine, t-pentadecyl primary amine, t-hexadecyl primary amine, t-octadecyl primary amine, t-eicosyl primary amine, t-tetracosyl primary amine, and t-triacontyl primary amine. These amines can be prepared by several methods well known to those skilled in the art. Specific methods for preparing the t-alkyl primary amines are disclosed in the Journal of Organic Chemistry, vol. 20, page 295 et seq. (1955). Mixtures of such amines are contemplated. These can be made from a polyolefin fraction (e.g., polypropylene and polybutylene cuts) by first hydrating with sulfuric acid and water to the corresponding alcohol, converting the alcohol to alkyl chloride with dry hydrogen chloride, and finally condensing the chloride with ammonia, under pressure, to produce a t-alkyl primary amine mixture.

The succinamic acids contemplated herein are effective to impart antistall properties to motor gasolines. The amount of succinamic acid that is added to the motor gasoline will vary between about 0.005 percent and about

0.50 percent, by weight of the gasoline. In preferred practice, amounts varying between about 0.01 percent and about 0.05 percent, by weight, are used.

The antistall additives of the invention may be used in the gasoline along with other antistall addition agents or other additives designed to impart other improved properties thereto. Thus, anti-knock agents, pre-ignition inhibitors, anti-rust agents, metal-deactivators, dyes, antioxidants, detergents, etc., may be present in the gasoline. Also, the gasoline may contain a small amount, from about 0.01 percent to about 1 percent, by weight, of a solvent oil or upperlube. Suitable oils, for example, include Coastal and Mid-Continent distillate oils having viscosities within the range of from about 50 to about 500 S.U.S. at 100° F. Synthetic oils, such as diester oils, polyalkylene glycols, silicones, phosphate esters, polypropylenes, polybutylenes and the like, may also be used.

The following examples are for the purpose of illustrating the additives of this invention and demonstrating the effectiveness thereof. This invention is not to be limited to the specific compositions set forth in the examples or to the operations and manipulations involved. Other materials and formulations as described hereinbefore can be used, as those skilled in the art will readily understand.

The amine reactants used in the examples are mixtures of pure amines. "Amine A" is a mixture of primary amines having a tertiary carbon atom of a tertiary butyl group attached to the amino ($-\text{NH}_2$) group and containing 12 to 15 carbon atoms per molecule and averaging 12 carbon atoms per molecule. This mixture contains, by weight, about 85 percent t-dodecyl primary amine, about 10 percent t-pentadecyl primary amine, and relatively small amounts, i.e., less than 5 percent amines having less than 12 or more than 15 carbon atoms. "Amine B" is a mixture of tertiary alkyl primary amines containing 18 to 24 carbon atoms per molecule and averaging about 20 carbon atoms per molecule. It has a tertiary carbon attached to the $-\text{NH}_2$ group. It contains, by weight, about 40 percent t-octadecyl primary amine, about 30 percent t-eicosyl primary amine, about 15 percent t-docosyl primary amine, about 10 percent t-tetracosyl amine, and a small amount, less than 5 percent, other amines.

EXAMPLE 1

A mixture of 100 grams (0.5 mole) of amine A, 50 grams (0.5 mole) of succinic acid anhydride, and 50 grams of xylene, as diluent, was heated with agitation to 80-85° C. for 3 hours to form the succinamic acid. The reaction product was clear and fluid at room temperature.

EXAMPLE 2

A mixture of 152 grams (0.5 mole) of amine B and 50 grams (0.5 mole) of succinic acid anhydride was stirred for 2 hours at 110° C. to form the amine B succinamic acid.

Antistalling effectiveness

The ability of the succinamic acids of this invention to inhibit engine stalling is demonstrated in the following test:

A standard Chevrolet engine, equipped with a Holley single downdraft carburetor, was mounted in a "cold" room refrigerated to 50° F. A Holley carburetor was used. A thermocouple was attached to the throttle plate shaft to record the plate temperature. A $\frac{1}{2}$ -inch insulating gasket was placed between the carburetor and manifold to prevent heat conduction. An asbestos sheet covered the entire manifold system to shield the carburetor from convection and radiation. A spray chamber was used to saturate the incoming air with moisture before entering an ice tower which cooled the air to about 35° F.

In conducting a test, the engine was first run for about

10 minutes at 2000 r.p.m. to bring the engine temperature to equilibrium. The engine was then shut off. When the throttle shaft temperature rose to 40° F., the engine was restarted with the idle speed set at 400 to 500 r.p.m. so that the base fuel stalled at idle in 10 seconds or less after a run-time of 20 to 40 seconds. Run-time means the time that the engine was run at 2000 r.p.m. before returning to idle.

All runs were started when the throttle shaft reached 40° F. At the instant of starting, the throttle arm was moved to the 2000 r.p.m. position and a stop watch started. At the end of the selected run-time, the throttle arm was moved to the idle position. The time required to stall was recorded. Several tests were made at each run-time and averaged.

In evaluating an additive, the base fuel was first tested followed by several concentrations of the additive. The system was flushed between tests with the fuel to be run next. Any improvement caused by the additive was reflected in a longer run-time (as compared to the base fuel) to cause stalling in 10 seconds or less when the engine was idled. The more effective the additive, the longer the run-time.

Two test gasolines were used. "Gasoline X" was made up, by volume, of 63 percent catalytically cracked gasoline, 17 percent straight run gasoline, 8 percent benzene, and 12 percent toluene. It had an ASTM boiling range of 104° F. to 390° F., with a 50 percent distillation (mid-boiling) point of 203° F. "Gasoline Y" comprised, by volume, 66 percent catalytically cracked gasoline, 2 percent straight run gasoline, 12 percent benzene, 8 percent toluene, and 12 percent butanes. It had an ASTM distillation range of 80° F. to 296° F. and a mid-boiling point of 200° F.

The results of a series of stalling tests on these gasolines and on the gasolines containing varying amounts of the compound of Example 1 are set forth in the following table.

TABLE

Test No.	Compound Added	Gasoline	Conc'n, Wt. Percent	Run Time to 10 Sec. Stall Time (Sec.)
1.....	None.....	X	0.0	80
2.....	Example 1.....	X	0.01	130
3.....	.....do.....	X	0.02	130
4.....	None.....	Y	0.0	60
5.....	Example 1.....	Y	0.013	100
6.....	.....do.....	Y	0.005	120

From the data in the foregoing table it will be noted that the succinamic acids contemplated herein are effective to prevent icing and stalling. Although not exactly equivalent in effectiveness, other additives as defined herein are also useful to prevent stalling.

Although the present invention has been described with preferred embodiments, it is to be understood that modifications and variations may be resorted to, without departing from the spirit and scope of this invention, as those skilled in the art will readily understand. Such variations and modifications are considered to be within the purview and scope of the appended claims.

What is claimed is:

1. A motor gasoline containing a small amount, sufficient to prevent stalling, of a compound having the formula;

wherein R is a tertiary alkyl group containing between about 10 carbon atoms and about 30 carbon atoms and having a tertiary carbon atom directly attached to the nitrogen atom.

2. A motor gasoline containing between about 0.005 percent and about 0.50 percent, by weight of the gasoline, of a compound having the formula;

wherein R is a tertiary alkyl group containing between about 10 carbon atoms and about 30 carbon atoms and having a tertiary carbon atom directly attached to the nitrogen atom.

3. A motor gasoline containing between about 0.005 percent and about 0.50 percent, by weight of the gasoline, of a compound having the formula;

wherein R is a mixture of tertiary alkyl group having a tertiary carbon atom directly attached to the nitrogen atom.

atom and comprising about 85 weight percent dodecyl, and about 10 weight percent pentadecyl.
